UNITED STATES PATENT OFFICE.

DAVID LAMPERT, OF CHICAGO, ILLINOIS.

DESIGN FOR A FINGER RING.

Application filed February 11, 1924. Serial No. 8,605. Term of patent 7 years.

To all whom it may concern:

Be it known that I, DAVID LAMPERT, a citizen of the United States, residing at Chicago, in the county of Cook and State of Illinois, have invented a new, original, and ornamental Design for Finger Rings, of which the following is a specification, reference being had to the accompanying drawing, forming part thereof, and in which—

Fig. 1 is a top plan view, and Figs. 2, 3 and 4 are side views of a ring embodying the invention.

I claim:

The ornamental design for a finger ring as shown.

DAVID LAMPERT.
